UNITED STATES PATENT OFFICE

FRANK H. LINDBERG, OF COLUMBUS, OHIO

INTERNAL-COMBUSTION ENGINE

Application filed October 15, 1927, Serial No. 226,469. Renewed November 19, 1929.

This invention relates generally to improvements in internal combustion engines and, with regard to the more specific features thereof, is directed particularly to an improved valve mechanism adapted for use in connection with such engines, and wherein the valve mechanism is of such form as to include but a single head which is positioned vertically in one end of the explosion chamber and is operated in connection with yieldable valve seats for controlling both the inflow and outflow of the gases into and from the explosion chamber or chambers of the engine.

15 Among the objects of the invention are: The provision of a valve mechanism of simple and improved form designed especially for use in connection with internal combustion engines and wherein the single valve head or member is so formed as to be protected from the heat of the hot gases generated in the explosion chamber and the exhaust passage of the engine, the construction of the valve mechanism being such that the 20 stem proper of the single valve head or member will at no time be exposed directly to such heated gases, the stem portion of the valve being positioned in the intake passage of the engine and maintained in a relatively 25 cool condition by the sweep of the incoming fresh fuel mixtures; second, in the provision of a valve mechanism characterized by a silent operating property, and free from the clatter and noise of the usual poppet type of 30 valve with rigid seat, which the valve mechanism herein most closely resembles; third, in the provision of a valve mechanism which will be convenient to assemble in its operating position within the engine and also capable of being readily and quickly demounted and removed from association with the engine for replacement, adjustment or for 35 grinding and carbon removing purposes; and fourth in a valve mechanism wherein maximum orifice area is afforded to facilitate the entrance and exhaust of the gases to and from the explosion chamber when a single valve structure is taken into consideration.

While the invention has been set forth as 40 being particularly adapted for use in inter-

nal combustion engines, nevertheless in certain of its aspects the invention is of broader scope and may find use in other fields such as in pumps, compressors and the like.

Other objects will be in part obvious and in part pointed out hereinafter.

The invention consists in the combinations of elements and arrangements of parts hereinafter to be more fully described and pointed out in the appended claims.

In the accompanying drawing:

Figure 1 is a vertical sectional view taken transversely through the cylinder construction of an internal combustion engine and disclosing particularly the improved valve mechanism comprising the present invention.

Figure 2 is a transverse vertical sectional view taken on the plane indicated by the line 2—2 of Figure 1.

Figure 3 is a side elevation of the engine and the operating gear for the valve mechanism, portions of the case of the engine being broken away as shown in section to disclose interior structure.

Figure 4 is a transverse vertical section on the line 4—4 of Figure 1.

Figure 5 is a similar view on the line 5—5 of Figure 1.

Figure 6 is a fragmentary vertical sectional view disclosing the valve operating mechanism.

Referring more particularly to the drawing the numeral 1 designates the cylinder structure of an internal combustion engine, the numeral 2 a piston slidably mounted within said cylinder structure and connected by means of a connecting rod 3 with a crank shaft 4, rotatably mounted as usual within the crank case 5 of the engine. Mounted upon the upper portion of the cylinder structure is a cylinder head 6, which is formed to include a dome shaped cavity 7 which forms a part of the explosion chamber 8 of the cylinder structure above or to one end of the piston 9. The chamber 8 communicates by means of a substantially annular depression 9, formed in the head 6 with a longitudinally extending valve chamber 10 bored longitudinally through the cylinder head 6 from one side 100

of the latter to the other. Communicating with this chamber on opposite sides of the center line of the cylinder structure are gas inlet and exhaust passages 11 and 12 respectively, the former leading to the carburetter, not shown, of the engine and the latter to the atmosphere.

Mounted for yieldable movement axially of the chamber 8 are longitudinally spaced inlet and exhaust sleeves 13 and 14 respectively, which have their adjacent end portions oppositely chamfered to produce opposed valve seats 15 and normally arranged to engage with both of these seats is the peripheral portion of the valve head 16. This head is positioned transversely of the chamber 8 and is arranged substantially in the plane of the center line of the cylinder structure 1. The longitudinally extending stem 17 of the valve head is slidably received within a guide member 18, which is securely fastened to one end of the head 6 so as to close that end of the chamber 10. A coil spring 19 engages with and surrounds the guide member 18, and the inner end of the spring 19 bears upon an annular shoulder 20 formed internally of the inlet sleeve 13, so that said sleeve will be forced inwardly by the spring 19 to engage with the peripheral portion of the valve head 16, as shown in Figure 1.

The forward movement of the sleeve 13, in response to the influence of the spring 19, is limited by providing the outer end of the sleeve 13 with a flange 21 which is pressed inwardly by the spring 19 to engage with a yieldable abutment which in this instance has been shown to consist of a strong coil spring wound in such manner as to possess but limited expansive movement but capable of strongly resisting compression, this latter spring is indicated by the numeral 22. Also, the sleeve 13 may be provided with one or more compression rings 23, so disposed as to engage the circular walls of the chamber 10, and which rings operate, in the usual manner, to prevent seepage of gas past the joints provided between the meeting surfaces of the sleeves 13 and the walls of the chamber 10. The sleeve 13 in this instance is formed to include a plurality of longitudinally extending slots 24, which are adapted to register with the gas inlet passage or manifold 11 provided in the head 6. By means of a valve gear, hereinafter described, the valve head 16 may be moved toward and away from the inner end of the sleeve 13 to control the inflow of the fuel mixture into the explosion chamber of the cylinder.

The exhaust sleeve 14 consists of a hollow metallic body provided with a curved passageway 25, the inner end of which being normally closed by the valve head 16 while the outer end of said passageway is arranged normally in registration with the exhaust passage 12 of the cylinder head. Connected axially

with the outer portion of the sleeve 14 is a rod 26, which is slidably received within a guide opening provided in a cap member 27 which is removably connected with and adapted to close the opposite side of the chamber 10 as regards the guide member 18. The outer end of the rod 26 is in this instance slotted as at 28 for the reception of a cotter pin 29 which passes through openings provided in a box like extension 30 formed upon the cap member 27. This cotter pin also serves to secure a seating ring 30' to the outer end of the extension 30. The extreme outer end of the rod 26 is provided with a head 31, and the inward movement of the rod 26 and its associated sleeve 14 is limited by the engagement of the head 31 with the ring 30'. Outward movement of the sleeve 14 is limited by the engagement of the outer portion of said sleeve 14 with a centering extension 32 formed with the member 27 and located in one end of the chamber 10. A coil spring 33 surrounds the rod 26 and is confined between a collar 34 fixed upon the outer end of the sleeve 14 and an annular shoulder 35 formed internally of the extension 30. The normal action of the springs 33 is to maintain the inner portion of the sleeve 14 in engagement with the peripheral portion of the valve head 16. Piston rings 36 are carried by the sleeve 14 and contact with the adjacent walls of the chamber 10 to prevent undue passage of gas between the walls of the sleeve 14 and the adjacent walls of the chamber 10.

To effect the timed operation of the valve mechanism described, the crank case 5 is provided with a cam shaft 37, driven in any suitable manner from the crank shaft 4. This shaft 37 is formed to include for each cylinder of the engine a pair of cams 38, fixed for rotation upon and with the cam shaft 37. Adjacent to the cam shaft 37 there is arranged within the crank case a rocker shaft 39. This shaft is provided with a pair of fixed arms 40 and 41, the former of which extending above and over the shaft 37, and the latter being arranged to extend downwardly to a point below the cam shaft. The outer ends of the arms 40 and 41 are provided with rollers 42, which are adapted to ride upon and engage with the irregularly formed peripheral surfaces of the cams 38, whereby as the cam shaft revolves the rocker shaft will be given a periodic oscillatory movement.

Connected rigidly with the arms 40 and 41 is a third arm 43 to the outer end of which is pivotally connected as at 44 the lower end of a vertically extending lift rod 45 which is adapted to be reciprocated by the oscillatory movement of the rocker shaft. The rod 45 extends upwardly through an opening 46 formed in the top of the crank case and has its upper end pivotally connected as at 47 with one arm of a bell crank lever 48 which is fixed for oscillatory motion about a pivotal

axis 49 and is supported by ears 50 extending laterally from the cylinder head structure. The upwardly extending arm of the bell crank lever terminates in a ball shaped head 51, which is receivable within an opening or slot 52 formed in the outer end of the valve stem 17. An adjusting screw 53 is carried by the extreme outer end of the stem 17 and cooperates with the head 51 to provide for positive operation on the part of the valve gear and to prevent looseness and rattle and to reduce friction.

In the operation of the above described engine, it will be seen that when the piston 2 moves downwardly on its intake stroke the valve gearing operates to force the valve head 16 normally against the seat provided by the sleeve 14, and to move said sleeve in an outward direction against the influence of the spring 33. It will be observed that the sleeve 13 can not follow the advancing valve head 16, since this movement is limited by engagement with the abutment 22. This permits of the inflow of the fuel mixture by way of the passage 11, the sleeve 13 and thence by way of the annular port 9 into the cylinder head. The incoming gases contact with the stem and head of the valve 16 so as to effect the cooling thereof and to prevent the heat of the engine from cracking, warping or detrimentally effecting the structure of the valve 16. Also a wide unrestricted fuel passage is provided which permits of relatively unrestricted flow of the fuel mixture into the explosion chamber of the cylinder structure. This inflow of fuel is continuous with the fuel inlet passages in open condition until the piston reaches substantially the bottom of its intake stroke, at which point the valve gear is operated to return the valve part to the normal position disclosed in Figure 1, enabling the piston to advance in an upward direction on its compression stroke. Maximum compression can be obtained by reason of the fact that the valve sleeve 13 and 14 closely engage with the peripheral edge of the head 16, and also by use of the packing wings around the outer circumferential walls of the sleeves 13 and 14. During the firing stroke the valves also remain in their closed positions and upon the final up or exhaust stroke of the engine the valve gear operates to move the valve head 16 in an outward direction together with the sleeve 13. This is accomplished against the resistance offered by the spring 19, and permits the valve head 16 to draw away from the peripheral inner edge of the exhaust sleeve 14, thereby permitting the spent or exhaust gases to flow from the explosion chamber by way of the passage 25 in the exhaust sleeve 14 and thence through the exhaust conduit 12 leading from the engine.

In view of the foregoing description taken in connection with the accompanying drawings, it will be seen that the present invention

provides a novel valve mechanism for use in internal combustion engines, comprising essentially a single balanced valve so positioned as to be uninfluenced to any practical extent by the heat of the exhaust gases or operating temperatures of the engine. In the ordinary type of tappet valve the exhaust gases in leaving the cylinders, sweep around the valve stems of such valves and cause the latter to crack, warp and deteriorate. This deleterious effect is eliminated in the present design, inasmuch as the stem 17 of the single valve used is subjected merely to convected heat and is kept in a relatively cool condition by the incoming cool fuel charges, and in no instance is the valve stem proper exposed to the heat of the exhaust gases directly. Again, the construction admits of the attainment of greater valve or orifice area than in the employment of a tappet valve of given head diameter, inasmuch as the operation of the yieldable sleeves permits of a full and complete opening of the ports leading to the cylinder heads and therefore provides for full and complete inflow and exhaust of gases to and from the engine cylinder. Other features provided by the invention are: Reduction in noise or, stated in another way, silently operating valve mechanism. This has been very difficult to obtain in a tappet type valve mechanism operating in the head of an engine and, finally, the provision of a valve mechanism of extremely simple design, capable of being readily demounted from its operating position in the engine head for adjustment or valve grinding purposes.

Various changes in the form, proportion, and minor details of construction may be resorted to without departing from the principle or sacrificing any advantages of this invention.

What is claimed is:

1. In an internal combustion engine, in combination, a cylinder structure including a head, said head being formed to include a transversely extending valve chamber, there being spaced inlet and exhaust passages provided in said head on opposite sides of said chamber, sleeves slidably mounted in said chamber, a valve member positioned transversely within said chamber and situated between the adjacent end of said sleeves, and operating means for said valve member, said means serving to operate said valve member to effect relative separation of said sleeve and to establish collectively communication between said cylinder and one or the other of said passages.

2. In an internal combustion engine, in combination, a cylinder and a head at one end of said cylinder, said head being formed to include a valve chamber extending transversely thereof, there being spaced inlet and exhaust passages provided in said head and communicating with opposite sides of said

- chamber, said head being also formed to include an intermediate passage for establishing communication between the center of said valve chamber and said cylinder, sleeves slidably mounted in the opposite sides of said chamber and positioned normally so that the adjacent inner ends thereof will close said intermediate passage, a valve member positioned transversely of said chamber and including a head and a longitudinally extending stem, the peripheral edge of the head being engaged normally by the inner end of said sleeves, and operating devices cooperative with the stem of said valve member for effecting at timed intervals relative separation between said sleeves so as to open said intermediate passage and establish communication between the cylinder and the inlet and exhaust passages.
3. In an internal combustion engine, in combination, a cylinder structure including a working cylinder and a perpendicularly disposed valve chamber at one end of said cylinder, said cylinder structure including spaced inlet and exhaust passages communicating with opposite sides of said chamber and with an intermediate passage for establishing communication between said working cylinder and said valve chamber, spaced relatively movable slidably mounted sleeves positioned within said chamber and provided with ports arranged to register with said inlet and exhaust passages and with open inner ends communicating with said intermediate passage, a valve member including a head positioned transversely of said member and arranged normally between the meeting ends of said sleeves, means operating upon said sleeves to maintain the inner ends thereof normally in seating engagement with the peripheral portion of the head of said valve member, said valve member being provided with a stem located in the fuel inlet side of said chamber, and an operating mechanism connected with said stem and serving at timed intervals to move said valve member and an associated sleeve away from the complementary sleeve so as to effect the opening of said intermediate passage so as to permit of the flow of gases between one or the other of said intake and exhaust passages and said working cylinder.
4. In an internal combustion engine, a cylinder structure including a working cylinder and a demountable head at one end of said cylinder, said head being formed to include a valve chamber extending transversely thereof, spaced inlet and exhaust passages communicating with opposite sides of said chamber and an intermediate passage establishing communication between the working cylinder and the center of said valve chamber, a pair of sleeves mounted for longitudinal sliding movement toward and away from each other within said chamber, flexible

means acting upon said sleeves to force the latter inwardly of said chamber toward each other, means for limiting the movement of said sleeves, a valve member positioned transversely of said chamber and having the peripheral edge thereof disposed between the adjacent ends of said sleeves, and means for actuating said valve member, said valve member upon actuation being adapted to move one or the other of said sleeves to effect the opening of said intermediate passage and to thereby establish gas flow communication between either said intake or exhaust passage and said working cylinder.

5. In an internal combustion engine, a cylinder structure including a working cylinder, and a transversely extending valve chamber at one end of said cylinder, there being inlet and exhaust passages formed in said cylinder structure and communicating with opposite sides of said valve chamber and a passage disposed between said intake and exhaust passages and establishing communication between said working cylinder and the center of said valve chamber, spring pressed sleeves slidably mounted in said valve chamber and having the adjacent ends thereof chamfered to provide valve seats, said sleeves being provided with ports registering with said intake and exhaust passages, a valve member including a circular head disposed transversely of said valve chamber and having the peripheral portion thereof engaged with the valve seat formed at the inner end of said sleeve, said valve member including an operating stem arranged to project axially through the intake side of said chamber, said stem terminating exteriorly of the cylinder structure, and operating mechanism cooperative with the outer end of said stem to effect at timed intervals reciprocation of said valve member, the reciprocation of said member serving to effect relative separation on the part of said sleeve and to thereby open said intermediate passage so as to establish communication between said working cylinders and said inlet and exhaust passages.

6. In an internal combustion engine, in combination, a cylinder structure, a movable piston within said cylinder, a head covering one end of said cylinder and providing a clearance space, there being a valve chamber mounted directly in such space or communicating at all times with it, a valve head and stem, a flexible or movable member acting as a seat for said valve head mounted in such valve chamber, and operating means to move such valve head into contact and out of contact with said flexible valve seat.

7. In an internal combustion engine, in combination, a cylinder structure, a movable piston within said cylinder, a head covering one end of said cylinder and providing a clearance space, there being a valve chamber mounted directly in such space or communi-

cating at all times with it, a single male valve with head and stem, a flexible valve seat on both sides of said valve head mounted in such chamber, a separate fluid passageway leading from outside the valve chamber and connecting each with one of the flexible valve seats and with the valve chamber and clearance space only when the valve head is out of contact with the flexible valve seat, and operating means to actuate the valve head into contact and out of contact with said flexible valve seats.

In testimony whereof I affix my signature.

FRANK H. LINDBERG.
